ATT'Y'S

UNITED STATES PATENT OFFICE.

GEORGE FREDERIC BISHOPRIC, OF OTTAWA, ONTARIO, CANADA.

ROOF OR WALL COVERING.

1,088,803.

Specification of Letters Patent. Patented Mar. 3, 1914.

Application filed June 4, 1913. Serial No. 771,707.

To all whom it may concern:

Be it known that I, GEORGE FREDERIC BISHOPRIC, a subject of the King of Great Britain, and resident of the city of Ottawa, 5 Province of Ontario, Dominion of Canada, have invented certain new and useful Improvements in Roof or Wall Covering, of which the following is the specification.

This invention relates to improvements in 10 roof or wall covering and the objects of the invention are to reduce the cost of construction of a roof or wall, the time necessary to place the same in position and generally to provide a simplified form of weatherproof 15 covering which may be rapidly applied with unskilled labor at minimum cost.

More particular objects of the invention are to enable the sheathing usually placed 20 on the rafters of a roof to be dispensed with and to provide an improved method of supporting and applying ready or manufactured roofing, and it consists essentially of ready or manufactured roofing material formed in strips or shingles adapted to be 25 laid overlapping each other, the underside of said strips or shingles having reinforcing means such as laths adapted to support the same in position from the rafters or the like, all as hereinafter more fully set forth and 30 described in the accompanying specification and drawing.

In the drawing, Figure 1 is a perspective view of the roof embodying the present invention. Fig. 2 is a perspective view of one 35 of the strips or shingles. Fig. 3 is an end view. Fig. 4 is an enlarged sectional detail through a few shingles.

Referring to the drawing, A represents a strip of ready or manufactured roofing or 40 like covering material cut substantially in the shape of a shingle. A variety of materials may be used for the purpose, for instance any of the well known ready or manufactured roofings formed from asbestos felt, 45 paper or asphalt or the like.

The form of material I have illustrated in detail in Fig. 4 comprises a foundation layer 10 of paper or asbestos felt, an upper layer 11 of asphalt or other suitable adhesive material with or without a coating

of sand. The strips or shingles A are, when laid, adapted to overlap each other and are provided with reinforcing or supporting means in the form of laths B which extend longitudinally of the strip or shingle. These 55 laths are provided only on the portion exposed on the underside and are adapted to rest on the rafters C or the like. In the embodiment illustrated, two parallel laths are provided on the underside near one edge and 60 spaced a short distance apart, the outermost lath being a distance from the edge of the strip substantially equal to the distance between the laths. The laths are held in position on the shingle by suitable means and I 65 find it desirable to combine the means for holding the laths in position with means which will give additional protection to the roof. To this end I provide a coating 12 of asphalt or the like on that portion of the 70 underside of the strip or shingle along which the lath extends so that the laths or like strips will be embedded in said asphalt while hot.

In constructing or laying a roof or wall 75 according to the present invention, the first row of strips or shingles A is laid at the end of the rafters so that the unreinforced portions 13 of the strips or laths will project beyond the end of the rafter to form a strip. 80 The laths B are nailed or otherwise secured to the rafters. The projecting rear portion 14 of the strips or shingles A will form a straight line and guide for the next row of strips or shingles, the portions 13 of which 85 will overlap the reinforced portions of the first row. This operation will be completed until the whole roof is laid.

It will be seen that when finished the underside of the roof will present a series of 90 parallel strips or laths securely fastened to the rafters and taking the place of the sheathing at present necessary, while the outer part of the roof will present a surface of overlapped shingles and ready roofing 95 material adapted to effectually resist the weather.

What I claim as my invention is:

1. A shingle for the purpose specified comprising a strip of roofing material hav- 100

ing parallel reinforcing means attached to said strip on the underside near one end.

2. A roofing shingle for the purpose specified comprising a strip of roofing material having a layer of asphalt on the underside and reinforcing strips embedded in the asphalt adjacent one end.

In witness whereof I have hereunto set my hand in the presence of two witnesses.

GEORGE FREDERIC BISHOPRIC.
